UNITED STATES PATENT OFFICE.

NELSON DE LONG, OF CHICAGO, ILLINOIS, ASSIGNOR TO BENJAMIN B. SALVATY, OF CHICAGO, ILLINOIS.

METHOD AND MEANS FOR TREATING SHEET MATERIAL.

Application filed May 29, 1924, Serial No. 716,646. Renewed January 10, 1929.

My invention relates to improvements in means and methods for treating sheet material, such as paper, and has special reference to improved means and methods for 5 drying the sheets themselves or material, such as ink which has been applied to the surface of the sheets. I have first worked out my improvements as applied specifically to the rapid printing of paper and, although 10 I have, in this present application, described my invention as applied to the printing of a paper web successively on opposite sides of the web with the smearing or offsetting of the first impression, by the pressure necessary for the second impression, eliminated, it will be obvious, upon a full understanding of the invention, that it is also applicable to the printing of separate sheets and the elimination of smut sheets which 15 are now commonly employed in this work.

A particular object of my invention in connection with the printing of paper is the elimination of the so-called smut roll which does not last long, the cost of which 25 is high and which requires constant surveillance to prevent additional cost through delays, etc., whenever the smut web becomes wrinkled or broken.

I accomplish my object by the peculiar 30 and novel application of heat and air to practically instantaneously eliminate all volatile elements of the impressed ink, and, under some conditions, the like chilling of the impressed ink after the volatile parts 35 have been thus removed.

It will become clear, from the following 40 description, that while I have illustrated my invention as applied to the rapid printing of paper webs on its opposite sides and the elimination of smut rolls and sheets, that 45 my invention is capable of application to many other uses, such as the rapid or quick drying of sheet material itself, as well as ink which may be impressed upon its surface.

My invention will be more readily understood by reference to the accompanying drawings, forming part of this specification, and in which I have illustrated a specific 50 application of my invention as applied to a web printing press, and in which drawings:

Figure 1, is a diagrammatic side elevation of a web printing press of usual con-

struction equipped with an ink drying mechanism constructed in accordance with my invention and which I have found best adapted for practicing my novel method;

Figure 2, is an enlarged side elevation of the ink drying mechanism, shown in Figure 1;

Figure 3, is a sectional view through one of the hot air applicators and its associate roll on the line 3-3 of Figure 2;

Figure 4, is a similar sectional view of the cold air applicator;

Figure 5, is an enlarged vertical sectional view of one of the applicators and its associated roll;

Figure 6, is a fragmentary plan view of one end of one of the applicators illustrating the means for adjusting the space between the applicator and its roll;

Figure 7, is a fragmentary end elevation of the parts shown in Figure 6;

Figure 8, is a fragmentary section on the lines 8-8 of Figures 5 and 7; and

Figure 9, is a diagrammatic sectional view illustrating the action of the thin film of air in transferring heat from or to the applicator.

In said drawings, 10 illustrates, diagrammatically a web press, adapted in the form shown, for printing on a paper web 11, first on one side by means of impression cylinders 12, 13 and 14, and then on the opposite side of the paper by the impression cylinders 15, 16 and 17.

Between the two sets of cylinders, I arrange means for drying and setting the ink 90 of the first impressions before the web reaches the second set of impression cylinders.

The paper web 11 is supplied in the form of a roll 18 and is led around suitable idlers 19 to the first set of impression cylinders where one or more impressions are made upon one side of the paper according to the results desired; it is then led to the drying mechanism designated generally by 20 and having a plurality of idle rolls or cylinders 21, 22 and 23, that is, three in this particular instance. From the drying mechanism the web 11 is led over suitable idle guide rollers 24 to the second set of impression cylinders, from which point it is trained over suitable idle guide rolls 25 for delivery from the printing machine to suit-

able cutting and folding mechanism, not shown, as may be desired, as shown by the dotted line, Figure 1.

The drying mechanism 20 consists of the three idle rollers 21, 22 and 23, which are duplicates of each other. Each cylinder or roll consists of a cylindrical shell 26 and heads 27. The roll is mounted on a central shaft 28 to which the heads are secured, and the shaft is rotatably mounted at its ends in suitable adjustable bearings 29. The bearings at each side of the machine, that is, the three at the same ends of the several cylinders are mounted on a channel beam 30.

15 The two channel beams are supported at one end by swinging hanger or radius arms 31 which are pivotally mounted at their upper ends on trunnions 32 mounted in bearing brackets 33. At their opposite ends the two

20 channel beams are mounted for easy up and down adjustment through a limited movement by means of link members 34, pivotally connected at their ends to the adjacent ends of the channel beams and at their upper ends 25 35, carried on an eccentric strap 36, mounted on eccentrics 37 secured on a cross shaft 38. A crank arm 30 is secured to one end of the shaft 38 by which the shaft can be rotated through 180° from the position shown to

30 lower the forward ends of the channel beams 30 in an obvious manner, and when the shaft is rotated back again the beams are raised and locked in their raised position. The channel beams 30 in their up and down movements, as described, obviously carry with them the three cylinders 21, 22 and 23, the up and down movement of which is for a purpose to be described.

The paper web, when it leaves the first set of impression cylinders, is first led around the cylinder 21, then down around a relatively small diameter idle roller 40. This roller 40 is rotatably mounted at its ends in adjustable hanger bearings 41 depending from the channel beams 30. The web is then trained around the second cylinder 22 and then is led down to the lower part of the machine around an idle roll 42, (see Figure 1) then up and around the third cylinder 23, then down around the idle rollers 24 to the second set of impression cylinders. The inking rollers for the impression cylinders are not shown.

Related to each of the cylinders 21, 22 and 23, is what we term an air applicator, shown respectively at 43, 44 and 45. The several applicators are substantially alike except that those shown at 43 and 44 are adapted to apply heat as well as air, and that shown at 45 is adapted to apply cold, or, in other words, extract heat as well as apply air. It should be understood that in the manner in which the paper is trained around the several cylinders 21, 22 and 23, the first printed surface is always presented outwardly.

Hot air or air in combination with heat has long been used to dry all kinds of material, but I am convinced that it has never been applied in such a manner as to efficiently apply the heat used nor to effect the 70 drying in as short an interval of time as I am enabled to by means of my invention. That this is true is evidenced by the fact that, so far as I am aware, no one has been enabled heretofore to print on the two opposite sides of a web of book or magazine paper in a web press, or for that matter in a sheet press without the use of a smut sheet or roll.

By means of the applicators 43 and 44 I 80 am enabled to apply heat and air in a manner to eliminate all of the volatiles from the first impressions, and by means of the applicator 45 I am enabled to chill or lower the temperature of the remaining ink to 85 such an extent that I do not produce any offset on the cylinder 15 in making the impressions by the cylinders 16 and 17. I have found that one reason prior methods have failed in efficiency is that all of the prepared 90 air is not made use of. To eliminate this detrimental feature I provide the applicators which are in the form of saddles or chests extending a little more than one-fourth around the cylinders, as best shown in Figure 5. These chests are each provided at their ends with trunnion bearings 46 which are received in suitable openings in channel supports 47, which channel supports are rigidly mounted on the frame of the press by brackets 48. The chests are clamped to the channels by nuts 49 on the outer ends of the trunnions 46 which are threaded to receive same. The nut clamps the web of the channel 47 against a shoulder 50 on the trunnion. The trunnions at both ends are hollow. At one end an air pressure pipe 51 is connected and which leads directly into a central longitudinal passage 52, through which the air is delivered to a longitudinal series of small ports or outlets 53 directed inwardly toward the cylinder with which the applicator cooperates. The inner end of each radial port 53 is flared or countersunk, as shown at 54, to provide an elongated emission opening at the surface of the cylinder sufficient to provide an emission area which is at least equal to or greater than what would be the emission area of an exit slot extending the length of the applicator. The 100 applicator is adjustable from and toward the cylinder by means, to be described, to provide a circumferential space 55 between the applicator and the cylinder of a few thousandths of an inch in radial thickness, probably never less than three times the thickness of the paper web being presented, this for the purpose of allowing the passage of wrinkles in the paper without tearing the web.

130

The hollow trunnion at the opposite end is closed by a hollow plug 56 threaded at its outer end to receive a steam supply pipe 57. I provide simple means for directing the steam into the hollow applicator and outside of the central passage 52. This means comprises an inner plug 58 closed at its inner end and open at its outer end for receiving the steam. The plug 58 is provided with radial passages 59 which lead into a circumferential groove 60, and an opening 61 leads through the wall of the applicator into the hollow space 72 surrounding the passage 52. I provide simple packing means 73 and 74 to prevent the escape of the steam along the outer surface of the two plugs 56 and 58. Suitable control valves 75 and 76 are provided for controlling the flow of air and steam to the applicator. The air which I use in connection with the steam for heating and drying the ink is preferably of but a few pounds pressure, in most instances not over two or three pounds, but even this low pressure is sufficient to drive the thin film of air between the applicator and the paper, which surrounds the cylinder, at a very high velocity. The projection of the air in the form of this extremely thin film at this high velocity causes the almost instantaneous extraction of the more volatile parts of the ink, and what is not extracted by the first application is extracted at the second application. It should be understood that if a certain quality of ink or paper required further applications of heat and air the scheme is capable of such development by the further application of the hot applicators.

Another inherent feature of the thin film method of applying the air results from the peculiar and efficient action of the air in transferring heat from the applicator to the paper in the case of the hot applicator and of transferring heat from the paper or ink to the applicator in the case of the cold applicator. I have illustrated this action in Figure 9, which is a fragmentary transverse section of an applicator and its associated cylinder greatly enlarged. The air is driven with great velocity through the slot 55 from the air outlets 54 and as the paper is in motion and the applicator is stationary, there is a differential of friction set up which would result in an undulating or rolling movement of the air, causing specific infinitesimal portions to contact with one wall of the slot and then with the other wall of the slot, as indicated by the advancing circles 55' in the slot 55 in Figure 9. This action greatly enhances the transfer of heat from one wall to the other in addition to the direct radiation possible through such a thin space. It is believed that this theory accounts for the remarkable efficiency of this method. Another feature of importance is

the high velocity of the film of air, which in turn is due to the pressure under which the air is applied. This velocity, which is estimated to be about 5,000 feet per minute, is sufficient to bring each portion of the paper web into contact with about 150 feet in length of the stream of air while the specific portion of the web is passing between an applicator and its associated cylinder. I have therefore condensed, or compressed, 75 into the small space of about fourteen inches, as to results, what would ordinarily require about 150 feet of length of the web. If the air has to be preheated to a high enough temperature to carry an equivalent amount 80 of heat to the paper, it would be raised to a temperature where it would ignite the paper. By my improved method I avoid such possibilities of danger. Furthermore, the air is maintained at substantially the 85 maximum temperature until it emerges from the space 55, that is, while confined in the slot it is working at maximum efficiency.

In order to be assured of the production and maintenance of the space between the 90 applicator and the cylinder of uniform radial depth throughout, I have provided simple means for adjusting the positions of the cylinders and the applicators. Part of this adjustable means is the adjustable bearings 95 by which the cylinders are carried and by which means the several cylinders can be accurately adjusted to properly track the paper web. The trunnion mounting of the applicators permit them to be tipped to 100 equalize the space at the forward and rear edges. In addition I provide spacing or pressure rollers 77, one at each edge at both ends of each applicator. Each pressure roller 77 is mounted for adjustment radially 105 and is adapted to contact with the surface of the cylinder, as shown in Figures 5 and 7. The applicator is provided with a recess or pocket 78 for receiving the roller and the roller is mounted on a pin 79, having a hex 110 head 80 and two concentric bearing portions 81 and 82. Between the bearing portions the pin is provided with an eccentric portion 83 upon which the roller 77 is mounted. It will now be obvious that by rotating the 115 pin the roller 77 can be adjusted in and out. The pin is held rigidly in its adjusted position by a set screw 84. It should be understood that the space 55 is very greatly exaggerated as to radial depth. 120

After leaving the two hot applicators 43 and 44, the web is carried down to the bottom of the machine around the idle roller 42 and then up again around the cylinder 23 and beneath the third applicator 45. 125 This relatively long travel of the web is for the purpose of allowing as much dissipation of heat as possible between the last hot applicator and the cold applicator at which point I reduce the temperature of the ink to a 130

point sufficient to set it or make it hard and prevent any offsetting in the operation of printing on the opposite side of the web. The chest in the cold applicator 45 is a duplicate of one of the hot chests, except that I do not provide any steam connection, closing one end of the central opening 52, see Figure 4, with a plug 85 and omitting the radial passage or port 61, the outer space 72 in this instance being merely a heat insulation space. The chest fits around the cylinder, as in the other instances, and is likewise held very close to the cylinder. The end of the passage 52 opposite to the plug 85 is closed by a plug 86 provided with a central passage 87 connected at its outer end with an air pressure supply pipe 88 controlled by a suitable valve 89. The inner end of the plug 86 is formed into an expanding nozzle 90, having a constricted passage 91 at its inner end. This is to cause the expansion of the high pressure air supplied to a larger volume and lower pressure within the passage 52, and simultaneously to produce a low or refrigerating temperature. The air is supplied at 50 to 60 pounds pressure and is dried and cooled to as low a temperature as convenient with ordinary city water, probably about 70° F. Such air when suddenly released and expanded drops down to about 40° F. or lower, and the pressure used within the applicator is similar to the hot applicators, viz, about 2 or 3 pounds. This low pressure cold air is applied in the same manner as in the hot applicators, viz, in the form of a very thin film the whole length of the applicator and is caused to flow over the paper web in both directions around the cylinder at a very high velocity. The application of the air in the manner described, besides the advantageous results mentioned, causes a balancing of the frictional drag on the paper and consequently does not accelerate or retard appreciably the forward movement of the paper web.

The peculiar mounting of the several cylinders on the channel beams 30 permits the quick and easy dropping of the three cylinders and their separation from the three applicators when it is desired to thread the web of paper through the machine. When the web has been threaded through then the pulling down of the crank 39 simultaneously lifts the three cylinders to proper working relation to their several applicators, and the relation of the centers of the lifting mechanism is such that the centers are passed and the frame is locked in raised position until unlocked by the swinging up of the crank 39. The chests of the two hot applicators 43 and 44 are each provided with drain pipes 92 by which the condensed steam may be removed.

It is to be noted that the relation of the several applicators to their respective cylinders

and to the pivots 32, upon which the framework is hung, is such as to permit the cylinders to drop freely away from the applicators and yet permit the draining of the two hot applicators by drain pipes 92, that is, from one side of each of the chests. Furthermore, they are arranged to give the maximum opening between the several cylinders and their respective chests, as the chests are centered in each case substantially upon an arc struck from the pivotal center 32 and passing through the center of the cylinder. This is illustrated by the arc 93 in relation to the applicator 43.

In Figure 1, besides the delivery of the web from the machine to suitable cutting and folding mechanism, as indicated by the dotting of the line indicating the web 11, I can and sometimes do provide a second set of applicators, as shown at 94, Figure 1. This second set of applicators may be the same as the first set already described, although I have illustrated but one hot applicator and one cold applicator. These are used for the purpose of drying and setting the ink impressed by the second set of impression cylinders before the web passes to the cutting or folding mechanism spoken of before.

It will now be clear that the paper when put into motion through the machine is first printed on one side, then the volatile parts of the ink are removed by the hot applicators, then the remaining ink is set by the cold applicator, then the opposite side of the web can be immediately printed without the use of a smut roll or web. It should be understood of course that the printing of the opposite side is not an essential feature of my invention, as the paper web might be removed from the machine without this step, but even so it must be either wound up again or cut into sheets, and in either case the first printed surface is bound to be pressed with greater or less pressure against the opposite side of the web, and by means of my invention this can immediately occur without any possibility of offsetting which is now the great bane of this class of printing.

I have thus fully described this particular application of my invention so that it might be thoroughly understood, but it should be clear that my invention is not limited to the specific sequence of steps described nor to the specific construction shown and described, particularly as it is obvious that many modifications will readily suggest themselves to one skilled in the art.

I claim:

1. The herein described improvements in printing paper, which consist in producing one or more ink impressions on one side of the paper, then causing relatively hot air to flow in contact with the printed surface of the paper at a relatively high speed, and

confining the air while in contact with the paper to the form of a relatively thin film and successively applying cold air in a similar manner.

5 2. The herein described method of printing a paper web, which consists in putting the web into motion endwise, and while it is in motion producing one or more ink impressions on one side of the paper, applying 10 air in the form of a relatively thin film to the printed surface, the air flowing over the surface at a relatively high velocity, and then applying air at a relatively low temperature to the moving web in like manner, 15 whereby the ink is set to prevent it smearing.

3. The herein described method of printing a paper web, which consists in putting the web into motion endwise, and while it 20 is in motion producing one or more ink impressions on one side of the paper, applying air in the form of a relatively thin film to the printed surface, the air flowing over the surface at a relatively high velocity, 25 and then applying air at a relatively low temperature to the moving web in like manner, whereby the ink is set to prevent it smearing, and then producing ink impressions on the opposite side of the paper.

30 4. The herein described means for applying heat and air to the printed surface of a sheet and comprising a roller around which the sheet passes, a hollow enclosing member conformed on its inner surface to the 35 periphery of the roll and positioned to provide a sheet-like space between the two, not more than a few thousandths of an inch in thickness, means for forcing air between the two at substantially the median line of 40 the enclosing member, and means for applying heat to the sheet as it passes between the two.

5. The herein described means for applying heat and air to one surface of a sheet, 45 such as a printed sheet of paper, and comprising a roller around which the sheet passes, a hollow enclosing member conformed on its inner surface to the periphery of the roll and positioned to provide a sheet-like 50 space between the two, means for forcing air between the two at substantially the median line of the enclosing member, means for applying heat to the sheet as it passes between the two, and means for adjusting 55 the radial thickness of the space between the roller and enclosing member.

6. The herein described means for applying heat and air to one surface of a sheet, such as a printed sheet of paper, and comprising a roller around which the sheet 60 passes, a hollow enclosing member conformed on its inner surface to the periphery of the roll and positioned to provide a sheet-like space between the two, means for forc-

ing air between the two at substantially the 65 median line of the enclosing member, and means for applying heat to the sheet as it passes between the two, the enclosing member being pivotally mounted so that it can be adjusted substantially concentrically with 70 the roller.

7. In a printing press in which paper is put into motion, and while in motion has one or more ink impressions applied on one side thereof, means in combination with the 75 press for applying air in the form of a relatively thin film and at relatively high velocity to the printed surface, means for simultaneously applying heat to the paper, and means for similarly and subsequently applying air at a relatively low temperature 80 to the paper, as and for the purpose specified.

8. In a printing press in which paper is put into motion, and while in motion has 85 one or more ink impressions applied on one side thereof, means in combination with the press for applying air in the form of a relatively thin film and at relatively high velocity to the printed surface, means for 90 simultaneously applying heat to the paper, means for similarly and subsequently applying air at a relatively low temperature to the paper, and means for subsequently producing one or more ink impressions on 95 the opposite side of the paper before it is discharged from the press.

9. In a web printing press adapted to first print one side of the web and subsequently print the opposite side of the web, means 100 arranged between the two points of impression to first apply heated air to the surface of the web in the form of a film of not more than a few thousandths of an inch in thickness and flowing at a relatively high velocity, and means for subsequently chilling the 105 ink before the second impression.

10. In a printing press adapted to put paper in sheet form into motion, and while in motion to first print one side thereof, and later print the opposite side thereof, means for subjecting the first printed side of the paper to the action of a film of air of not more than a few thousandths of an inch in thickness and flowing at high velocity, at a 110 point between the two impressions, and means for likewise subjecting the second impression before the paper is delivered from the press.

11. In a printing press adapted to put 120 paper in sheet form into motion, and while in motion to first print one side thereof, and later print the opposite side thereof, means for subjecting the first printed side of the paper to the action of a film of air of not more 125 than a few thousandths of an inch in thickness and, flowing at high velocity, at a point between the two impressions, and simul-

taneously applying heat to the treated surface of the paper, and means for likewise subjecting the second impression before the paper is delivered from the press.

5 12. In a printing press adapted to put paper in sheet form into motion, and while in motion to first print one side thereof, and later print the opposite side thereof, means for subjecting the first printed side of the 10 paper to the action of a thin film of air, flowing at high velocity, at a point between the two impressions, and simultaneously applying heat to the treated surface of the paper and successively likewise applying a thin 15 film of cold air, and means for likewise subjecting the second impression before the paper is delivered from the press.

13. In a printing press adapted to put paper in sheet form into motion, and while 20 in motion to first print one side thereof, and later print the opposite side thereof, means for subjecting the first printed side of the paper to the action of a thin film of air, flowing at high velocity, at a point between the 25 two impressions, and simultaneously applying heat to the treated surface of the paper and successively applying a second similar thin film of air and simultaneously extracting heat from the treated surface of the 30 paper, and means for likewise subjecting the second impression before the paper is delivered from the press.

14. The herein described method of treating sheet material, which consists in putting 35 the sheet material into motion, and while

in motion first impressing a liquid on one surface thereof, then applying a thin film of air, flowing at high velocity, to the impressed surface, then applying a second thin film of air to the impressed surface and 40 simultaneously extracting heat from the sheet material.

15. The herein described method of treating sheet material, which consists in putting the sheet material into motion, and while 45 in motion first impressing a liquid on one surface thereof, then applying in the form of a film of not over a few thousandths of an inch in thickness and flowing at high velocity, to the impressed surface and simultaneously extracting heat from the sheet material, then impressing liquid on the opposite side of the sheet material, and then subjecting the said opposite side similarly 50 to a thin film of air before the sheet material 55 comes to rest.

16. The herein described method, which consists in putting sheet material in motion, and while it is in motion applying a gaseous fluid to the surface of the sheet material on a line transversely of the direction of movement of the material and causing the fluid to flow in both directions along the surface of the material from the line of application 60 at relatively high velocity and in the form of a film of not more than a few thousandths of an inch in thickness.

In testimony whereof, I have hereunto set my hand, this 29 day of April, 1924.

NELSON DE LONG.
